UNITED STATES PATENT OFFICE.

BARTHOLOMEW O'KANE, OF CINCINNATI, OHIO, ASSIGNOR OF ONE-HALF
TO STELLA NOEL, OF CINCINNATI, OHIO.

AERIAL VESSEL.

No. 820,938.

Specification of Letters Patent.

Patented May 15, 1908.

Application filed August 22, 1904. Serial No. 221,654.

To all whom it may concern:

Be it known that I, BARTHOLOMEW O'KANE, a citizen of the United States, residing in the city of Cincinnati, in the county of Hamilton and State of Ohio, have invented a new and useful Aerial Vessel; and I do declare the following to be a clear, full, and exact description thereof, attention being called to the accompanying three sheets of drawings, with the reference characters marked thereon, which form also a part of this specification.

This invention relates to an aerial vessel in which the principles of parachute and aeroplane are combined, the first to provide buoyancy to aid sustainance in the air in opposition to the action of gravitation, the other to produce motion.

The invention consists of the means and their construction whereby such a vessel is practically produced.

In the following specification, and particularly pointed out in the claims following, is found a full description of the invention, together with its operation, parts, and construction, which latter is also illustrated in the accompanying three sheets of drawings, in which—

Figure 1 is an end view of the vessel with its propelling members in operation. Fig. 2 is a top view of it as it appears in Fig. 1. Fig. 3 is a side view of the same as it appears in the two preceding figures and more particularly when viewed from the left side. Fig. 4 shows a detail portion, on enlarged scale, of one of the parachute-wings. Fig. 5 is a longitudinal section of this figure—that is, a section on a horizontal line as this figure is viewed by the observer. Figs. 6 and 7 show in views similar to Figs. 4 and 5 parts of one of the propeller-wings. Fig. 8 is a view similar to Figs. 4 or 6 shows a modified arrangement of the blades of this propeller-wing. Fig. 9 shows a frame to guide and hold the helm of the rudder. Fig. 10 is an enlarged detail view of parts shown in the preceding figure.

The upper and as to area the largest part of the vessel consists of the parachute proper, resting on and connected to the upper part of the frame structure, as best shown in Figs. 1 and 2. The larger part of this parachute consists of a suitable flexible fabric, preferably waterproof, like rubber or oil-

cloth. At various points along its outer edge guy-ropes or cables 12 are provided, attached with their lower ends to the lower part of the frame structure, of which 13 represents the uprights, and which uprights are connected to each other at their upper and lower ends. For obvious reasons this frame structure should be constructed of the lightest material possible and providing at the same time the requisite strength and rigidity. Suitable metallic tubing will be preferable for this purpose. Supported on these uprights between their ends there is a platform or cab 14 to support occupants and to carry mechanism whereby the operating means are actuated. These means, meaning thereby the devices which cause the structure to rise, to be maintained at a certain elevation, and to move forward, consist, substantially, of wings arranged in pairs and disposed so as to project laterally from opposite sides of the frame structure to which they are hingedly connected in a manner to be free to oscillate—that is, to swing up and down thereon. They are furthermore connected to each other in a manner that all move together, so that by actuating one pair they all operate.

A represent the pair of the lower wings. B-B constitute the pair in the middle, they being of increased projection, and C-C are the upper ones, having the largest lateral projection. Each of these wings consists of a skeleton frame embracing parallel longitudinal members 15 and 16 at the inner and outer end or edges, connected by parallel intermediate ribs 17. The inner members 15 are in each case pivotally attached by brackets 18 to the upright frame members 13, from which they project. The material should here again be as light as compatible with the purpose and may be tubing for members 15 and 16, while the intermediate ribs are preferably made from tough and fibrous wood—like, for instance, the American bamboo.

The upper wings C-C form practically a part of the parachute, or, what is also the same, part of the parachute operates as a wing—that is, it partakes of the motion of the same, so that one performs in part the function of the other. For such purpose the fabric of the parachute attaches to the parallel longitudinal edges of the upper wings C-C—that is, to the end ribs 17 thereof—and rests also on the extended ends of inner members.

15 15 of these upper wings. At or near their outer free edges all the wings on the same side of the vessel are connected by links 19, so that by operating one of them all wings on 5 that side move. In case of wings A and B these links connect to their outer members 16, while in the case of wings C a stiffening-bar 21 is provided across them to which these links connect. To operate these wings, (as 10 shown in Fig. 1, full lines showing the upper position of the wings and dotted lines the lower one,) I provide a lever-arm 22 on the inner edge of each of the middle wings B, which by links 23 are attached to a suitable 15 actuating medium, whereby they are simultaneously operated, as best shown in Figs. 1 and 3. This actuating medium may primarily consist of a crank-shaft, to which these links are operatively connected so as 20 to act together, the operation being by man or mechanical power, suitable gearing being interposed to obtain the proper arrangement of speed and power. There is an additional wing D, supported on the under side of the 25 cab and connected for operation to one of the upper wings by means of links 23 and a stiffening-bar 24 on such wing.

All the wings are composed of parallel blades 25 (see Fig. 2 and details Figs. 4 to 8) 30 of suitable light and elastic material, these blades being at one of their edges attached to ribs 17, while their other edges are free to yield to the resistance of the air, their return to normal position being due to the elasticity 35 of this material. The wings by their motion swinging up and down do not only lift the structure, but they also sustain the same at elevation and in addition they drive the structure forward. As to the lower and middle 40 wings, this propeller action is a double or compound one—that is, they act in both their up and down movements—while as to the upper wings forward motion is exercised only at the upstroke. The forward motion is due 45 to the individual vibratory motion of the blades in each wing, which under the resistance of the air, while the wings swing through this latter assume during the up as well as down motion angular positions, operating 50 then as aeroplanes, which particularly on the upward stroke drive the structure forward. (See Figs. 6 and 7.)

The upper wings C operate only in a limited way, as before stated, and being intended 55 to act mainly as a parachute the blades of these wings do not yield on the downward stroke, so that at that time and also whenever the operative parts are at rest these wings, together with the connected fabric 60 part, form an impenetrable surface constituting the parachute before mentioned and providing the buoyancy, whereby, assisted by the motion of the wings, the structure is sustained in elevation. For such purpose there 65 is a lip 26, against which in wings C the free

edges of blades 25 strike on the downward stroke and are prevented from yielding in that direction, as best shown in Figs. 4 and 5.

The blades in the lower wing D operate the same as in wings B and A. It is not necessary in order to move forward that the wings be operated all the time. Thus, for instance, after arrived at a certain elevation, the structure may be left to itself and active operation cease. The parachute and its wings will resist a rapid descent, while blades 25 of the other wings, being flexed into an angular position by the resistance of the air, act as aeroplanes, which drive the descending structure at the same time forward. Thus progress may be made without driving the structure positively 70 directly forward and by merely relying on this incidental forward action while the structure is descending. Operated in this manner the path of motion would represent a zig-zag line in a vertical plane. There would be a rising branch in that line representing the rise of the vessel as obtained by active operation of the propellers. At the highest point 75 of this branch and as soon as active operation is stopped there would begin the descending branch of that line, such part of that line being, however, also inclined forwardly, since by the action of the aeroplanes the descending structure is at the same time driven forward. The lower wing D with its vibrating 80 blades 25 could also be used as a marine propeller to move this or any other vessel through the water, the action of the blades being similar to that of sculls.

27 is the rudder supported by means of a ball-joint 28 in a bearing contained in a brace 29, sustained between the rear uprights of the frame.

30 is the helm of the rudder. To facilitate its manipulation, I provide a guide-frame 31, (see Fig. 9,) supported on the general frame and having vertical and horizontal branches bent to the arc of the circle on which this helm swings and in which branches the end 105 of the helm may be moved to suit all positions. The extreme end of the helm being an enlarged separate member may be turned on the helm proper and carries a friction-spring 32, which by its pressure against opposite parts of the guide-frame holds the rudder in its adjusted position, said member, with the spring, being turned accordingly, when moving either in the horizontal or upright branch of frame 31. The blades of the 110 propeller-wings A, B, and D may also be arranged in a manner to be reversible, so that the direction of motion of the vessel may be changed without turning it around by means of the rudder. For such purpose, referring 115 to Fig. 8, the end of ribs 17 are rotatably set in the sides of members 15 and 16 at the edges of the wings. Each would have a short arm 33, all of which arms are connected to a shifter-bar 34, whereby all blades are simul- 120 125 130

taneously swung around. This adjustment by suitable links and levers is arranged so as to be accessible from the cab from whence it is manipulated.

5 Having described my invention, I claim as new—

1. In an aerial vessel, the combination of a cab, a frame containing upright members between which this cab is sustained, a parachute on top of the frame, having parts projecting on each side thereof and arranged to have pivotal motion thereon, vertically-spaced wings arranged in pairs pivotally attached to the sides of the frame, they being provided with feathering-blades and projecting laterally from the frame in opposite directions, feathering-blades provided also in the laterally-projecting parts of the parachute, links connecting each of the projecting parts mentioned with the wings on the respective side of the frame and mechanism in the cab for imparting an up-and-down motion to all wings and the lateral parts of the parachute simultaneously.
2. In an aerial vessel, the combination of a cab, a frame containing upright members between which this cab is sustained, a parachute provided on top of the frame, wings arranged in pairs pivotally attached to the sides of this latter from which they laterally project in opposite directions, an additional wing pivotally attached at its upper edge to the under side of the cab and to the longitudinal center thereof, from which it projects downwardly, links whereby this wing and all the laterally-projecting wings are connected for simultaneous movement and operatively-connected mechanism supported in the cab for imparting such simultaneous movement to the wings.
3. In an aerial vessel, the combination of a cab, a frame containing upright members between which this cab is sustained, a parachute provided on top of the frame beyond which it laterally extends on both sides, vertically-spaced wings arranged in pairs pivotally attached to the sides of the frame from which they project in opposite directions, the laterally-projecting portions of the parachute being also arranged to have a pivotal motion on the frame, links connecting these portions of the parachute and all the wings below them on a side for simultaneous movement,

operatively-connected mechanism in the cab to impart simultaneously to these portions of the parachute and to the wings, an up-and-down motion, feathering-blades provided in the wings and in the movable portions of the parachute, the blades in the wings being arranged so as to be free to yield in opposite direction at the up as well as down stroke of the wings, and stops provided for the blades in the parachute which prevent these blades from yielding on the downstroke.

4. In an aerial vessel, the combination of a cab, a frame containing upright members between which this cab is sustained, a parachute provided on top of the frame, which projects all around beyond the same, the laterally-projecting portions of the parachute being arranged by means of a pivotal connection to the frame to be capable of having an up-and-down motion thereon, wings pivotally attached to the sides of the frame and below the parachute, they being arranged in pairs and projecting laterally from the frame, an additional wing pivotally attached below the cab to the longitudinal center thereof, links whereby this wing, the laterally-projecting wings and the movable portions of the parachute are all connected for simultaneous movement and operatively-connected mechanism carried on the cab to impart such movement.

5. In an aerial vessel, the combination of means for effecting elevation and motion, a rudder for steering, a frame to guide the helm of this rudder, a brace on which this helm is supported with a ball-joint permitting adjustment in horizontal as well as vertical directions, and means to hold this helm in adjusted position.

6. In an aerial vessel, the combination of means for effecting elevation and motion, a rudder for steering, a frame, having horizontal and vertical branches to guide the helm of the rudder, the end of which helm is adapted to move in these guides and a friction-spring provided in this end to hold the helm in adjusted position.

In testimony whereof I hereunto set my signature in the presence of two witnesses.

BARTHOLOMEW O'KANE.
